UNITED STATES PATENT OFFICE.

JAMES STUART WALLINGFORD, OF PARIS, KENTUCKY.

GARMENT SUPPORTER.

Application filed February 24, 1922. Serial No. 538,825.

To all whom it may concern:

Be it known that I, JAMES STUART WALLINGFORD, a citizen of the United States, and a resident of Paris, in the county of Bourbon and State of Kentucky, have invented a new and Improved Garment Supporter, of which the following is a full, clear, and exact description.

This invention relates to garment supporters and has particular reference to an improved clasp element.

More specifically the invention contemplates a clasp element for use in connection with hose supporters which reduces to a minimum the tearing or destruction of the garment by distributing the supporting strain over a wider area of the garment.

Heretofore in garment clasps the supporting strain has been more or less centralized at one or a number of points which tends to cause tearing or breaking of the threads, resulting in runs in the stocking.

As a further object the invention aims to produce a clasp element for garment supporters which when properly associated with the garment positively insures the retention of the garment against accidental displacement, while at the same time permitting of the ready release and application thereof.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawing—

Figure 1 is a side elevation illustrating a clasp element constructed in accordance with the invention in associated relation with a hose supporter or suspender and operatively engaged with a stocking.

Fig. 2 is a sectional view therethrough taken approximately on the line 2—2 of Fig. 1.

Fig. 3 is a side elevation of a modified form of the invention.

Fig. 4 is a sectional view taken approximately on the line 4—4 of Fig. 3.

Referring to the drawings by characters of reference, A designates a hose or stocking and B the suspender of a hose supporter to

which the clasp element designated generally at C is attached. The clasp element C constituting the invention comprises a strip of material bent approximately medially of its ends to provide inner and outer straps 10 and 11, said straps being stitched in loop form adjacent their juncture to provide a transverse tunnel 12 for the reception of the attaching link 13 of the suspender B. The inner strap member 10 in the preferred embodiment of the invention has secured to the outer side of its lower free extremity a block 14 preferably of resilient material such as rubber, which block is formed with an inwardly and downwardly beveled upper end 15. The outer strap 11 which is of slightly greater length than the inner strap 10 has secured to its lower extremity a rectangular loop 16, the same being of greater length than its height and of a height slightly less than the height of the block 14 at its inner side. The loop 16 is preferably of a length greater than the length of the block 14. In use the upper edge of the garment or stocking A is arranged over the block 14 and the loop 16 is then engaged over the portion of the stocking encompassing the block as illustrated in the drawings. This arrangement places the supporting strain on the inner strap 10, while the outer strap 11 which is of greater length than the inner strap remains slack. The clasping action is caused by the tendency of the strain exerted downwardly against the lower arm of the loop 16 by the stocking A to impinge the upper arm into the transverse groove formed at the juncture of the beveled portion of the block with the inner strap 10 and it will be found that as the strain increases the impinging action of the upper leg increases likewise to preclude any possibility of accidental displacement.

It follows that as the strain decreases the impinging action is likewise decreased whereby the clasp is rendered automatic in its action due to the fact that the loop and block are of a relatively elongated nature, the supporting strain is distributed over a wider area to prevent centralization of the pulling strains. This arrangement obviates the necessity of employing a multiplicity of clasps in addition to adding to the life of the stocking. To release the clasp, it is only necessary to pull upwardly on the outer strap 11 until the upper arm of the loop 16 is free to be swung outwardly over the upper and outer edges of the block 14.

In the modified form of the invention illustrated in Figs. 3 and 4, the straps 10 and 11 carried by the suspender B are of identical formation with that of the preferred form and likewise the loop 16 carried by the lower end of the inner strap is of similar formation. In lieu, however, of the block 14 a buckle 17 is employed which includes upper, lower and intermediate arms 18, 19 and 20 connected by the end arms 21. The lower extremity of the inner strap 10 is passed between the upper and intermediate arms 18 and 20 under the lower arm 19 and finally looped and secured about the intermediate arm 20 to provide a headed member over which the upper edge of the stocking A is arranged and with which the wire loop 16 coacts in a manner identical with the preferred form of the invention. To engage 20 the loop 16 after the upper edge of the stocking has been arranged over the block 14 or the headed member set forth in the modification, the lower leg of the loop is passed over the portion of the stocking lying there- 25 over and drawn upwardly until the upper leg is clear to swing over the upper edge of the block or headed member. When the supporting strain is applied the stocking will exert a downward pull on the lower leg to 30 impinge the upper bight formed in the stocking against the juncture of the inner strap with the block or headed element.

I claim:

1. A clasp element for garment supporters comprising inner and outer straps having a common connection at their upper ends to each other and to a supporting element, a

block carried by the outer side of the lower extremity of the inner strap, said block having an inwardly and downwardly beveled upper edge, a loop member carried by the lower end of the outer strap having upper and lower arms the relative spacing of which is less than the height of the outer side of the block, said loop member adapted to be engaged over the block when the portion of the garment is arranged thereover to provide in the garment at the rear of said block a pair of oppositely disposed bights whereby a downward pull exerted on the lower arm 50 will impinge the upper bight in the receiving space formed at the juncture of the upper edge of the block with the inner strap. 45

2. A clasp element for garment supporters comprising an outer and inner strap, the latter carrying a block at its lower free extremity, said block having an inwardly and downwardly beveled upper edge, the former carrying a loop at its lower free end of greater width and lesser height than the block, said loop adapted to engage over the block when a portion of the garment is arranged thereover to provide in the garment at the rear of said block a pair of oppositely disposed bights whereby a downward pull exerted on the lower portion of the loop will impinge the upper bight in the receiving space formed at the juncture of the upper edge of the block with the inner strap, the said outer strap being of greater length than the inner strap whereby said outer strap will serve only as a means for associating the loop with the supporter. 55 60 65 70
